CLAIM

The ornamental design for a pole mounted light, as shown and described.

DESCRIPTION

FIG. 1 is a top plan view of a pole mounted light;
FIG. 2 is a bottom plan view of the pole mounted light;
FIG. 3 is a perspective view of the pole mounted light;
FIG. 4 is a rear elevational view of the pole mounted light;
FIG. 5 is a right hand elevational view of the pole mounted light;

FIG. 6 is a top plan view of a pole mounted light showing a second embodiment of the design, the sole difference being an arcuate arm;

FIG. 7 is a bottom plan view of the pole mounted light showing a second embodiment of the design, the sole difference being the arcuate arm;

FIG. 8 is a perspective view of the pole mounted light showing a second embodiment of the design, the sole difference being the arcuate arm;

FIG. 9 is a rear elevational view of the pole mounted light showing a second embodiment of the design, the sole difference being the arcuate arm; and,

FIG. 10 is a right hand elevational view of the pole mounted light showing a second embodiment of the design, the sole difference being the arcuate arm.
